LUBRICATOR

Filed Dec. 5, 1928

INVENTOR:

EMIL BABER,
By: *Albert Ringer*,
his Atty.

UNITED STATES PATENT OFFICE

EMIL BABER, OF LOS ANGELES, CALIFORNIA

LUBRICATOR

Application filed December 5, 1928. Serial No. 323,918.

This invention relates to devices used for feeding lubricating oil into the combustion chamber of an internal combustion engine and thereby to parts generally not directly lubricated.

One of the objects of this invention is to provide a simple device with wick-feed supplying means whereby a certain amount of the lubricant is brought to a certain level in a suitably fine state.

Another object is to provide means whereby air is drawn into and through the wick-feed supplying means so that the wick is maintained in a suitably dry state to continuously draw the lubricant upwardly.

Another object is to provide means to prevent a splashing of the lubricant into the discharge.

Another object is to provide a comparatively small lubricant drawing tube extending into the wick whereby both, the air as well as the lubricant are compelled to first pass through the wick before passing into the lubricant drawing tube.

Another object is to provide an attachment to be secured to the top of a lubricant holding container with the wick enclosed tube extending to a point near the bottom of the container.

Another object is to provide means for adjusting the passage through which the lubricant can escape.

Other objects will appear from the following description and appended claims as well as from the accompanying drawing, in which—

Fig. 1 is a vertical midsectional view of a simple attachment with a wick-feed center tube by which a lubricant is brought close to the lubricant draw tube according to this invention, the attachment being shown in proper relation to the top of a glass jar.

Fig. 2 is a plan view of the underside of the attachment illustrated in Fig. 1.

Devices of this type are preferably connected to the manifold or intake of the internal combustion engine, so that the lubricant is drawn into the combustion chamber of the engine together with the gas intake.

As illustrated, the suction of the engine to

which this device is eventually applied acts in the direction of the arrow 3 so that a lubricant is drawn through the passage 4 of the connection 5 in the direction of the arrow 6 from the draw-tube 7. The set- and adjusting screw 8 serves for a proper control of the amount of lubricant to be drawn from the lubricant-holding container 9.

In the drawing, the lubricant-holding container 9 is illustrated in form of a glass jar but it must, of course, be understood that the container may be made of any other suitable material, the glass jar merely serving to facilitate an observing of the proper functioning of the whole device.

Several slanting bead-like members or projections 10 are provided near the upper edge of the container 9 by which the container is held to the attachment proper.

The attachment proper consists of a bracket-portion 11 and a cap-like portion 12. The cap-portion 12 is provided on its underside with tapped holes for the screws 13, to hold the washers 14 by which the container is held to the attachment proper, the washers engaging over the bead-like members or projections 10 in the manner of a threaded engagement or interconnection. A packing and baffle plate 15 is disposed between the top, being the attachment proper, and the container 9, thereby sealing the top to the container.

The top or cap-portion 12 is hollow and so formed as to provide a suitably large chamber 16 in the top above the packing and baffle plate 15. Small apertures 17 are provided in the top by which air can pass into the top and thereby into the container in the direction of the arrows 18 and 19 in proportion to the amount of lubricant drawn from the whole device, so that the withdrawn lubricant is replaced by air.

Besides the comparatively small draw-tube 7, a larger tube 20 is provided to extend from the hollow of the cap-portion 12. This larger tube 20 is filled with a suitable medium to bring the lubricant from the container to a level to be within reach of the draw-tube 7.

While wick-material is illustrated and indicated at 21, it must be understood that any

medium adapted to operate and function on the principle of capillary attraction, such as a sponge, a bundle of fine tubes, or wire can be used to bring or elevate the level, or 5 particles of the lubricant within reach of the draw-tube 7.

The draw-tube 7 is in this manner not in direct touch with the bulk of the lubricant in the container and can draw only from the 10 capillary medium such particles of the lubricant that have been brought within reach of the draw-tube by this medium.

Apertures 22 serve to admit air from the chamber 16 to the inside of the larger tube 20 in the direction of the arrows 23, being at the 15 point from where the draw-tube receives its lubricant, this also tends to develop a suitable dryness at this point so as to promote a proper functioning of the capillary medium.

The lubricant from the container 9 gradually rises in the direction of the arrows 24 20 by means of the capillary medium through the tube 20, to be drawn by the tube 7 towards the discharge in the direction of the 25 arrow 3.

Having thus described my invention, I claim:

1. In a lubricator of the class described, a 30 lubricant-holding container, a cap removably applied to the top of the container, a discharge-connection in the cap, the cap being also provided with air vents, a capillary feeding medium between the said connection in the cap and the container extending to a point 35 near the bottom of the container and a tubular member extending from said connection into the body of the said medium.

2. In a lubricator of the class described, a lubricant-holding container, a cap for the 40 container having a discharge-connection and air-vents, a tubular member extending from the inside of said cap to a point near the bottom of the container in communication with said connection and having air-vents at a point near the cap, a capillary medium in said 45 tubular member, and another comparatively small tubular member firmly seated in said cap and extending to a point near said air-vents in said first-named tubular member 50 within the body of said medium forming the communication between the medium and the said connection and thereby between the container and said connection.

3. In a lubricator of the class described, a 55 lubricant-holding container, a cap for the container having a discharge-connection and air-vents, a tubular member extending from said cap to a point near the bottom of the container and having air-vents at a point near 60 said cap, a baffle between the cap and the container below the air-vents in said tubular member, a capillary medium in said tubular member, and another comparatively small tubular member extending from the cap in 65 communication with said connection into the

body of said medium to a point near said vents in said first-named tubular member.

In testimony that I claim the foregoing as my invention I have signed my name.

EMIL BABER.
